SUPPORT

Leonard B. Paul, Joliet, Ill., assignor of one-third to George A. Lofdahl, one-third to Alice O'Mera Paul, and one-third to William Janke, all of Joliet, Ill.

Application November 23, 1937, Serial No. 176,118

4 Claims. (Cl. 248—223)

My invention relates to the disposition of ash trays, cigarette packages, matches, and the like, and includes among its objects and advantages the provision of an improved supporting shelf designed for detachable connection with lamp standards, tables, or the like.

An object of my invention is to provide a supporting shelf embodying novel clamp means for detachable connection with supports of variable proportions and in which the shelf includes means for supporting a cigarette package, a match box, as well as a supporting surface for an ash tray.

Another object is to provide a device of the type described which may be stamped from sheet metal and in which the device comprises two principal parts.

Another object is to provide a device of the type described in which the shelf is detachably connected with a supporting clamp and in which provision is made for shifting the relation of the clamp to the shelf in such a manner as to make the unit applicable to vertical as well as horizontal supports.

Another object is to provide a device of the type described in which a shelf is detachably connected with a supporting clamp and in which the shelf and the clamp are so shaped as to have inter-fitting relation for connecting purposes.

In the accompanying drawing:

Fig. 1 is a perspective view of the invention applied to a lamp standard;

Fig. 2 is a sectional view along the line 2—2 of Fig. 1;

Fig. 3 is a sectional view along the line 3—3 of Fig. 2; and

Fig. 4 is a perspective view illustrating the clamp and the shelf in detached relation.

In the embodiment selected to illustrate my invention, I make use of a shelf 10 semi-circular when viewed according to Fig. 2 and integrally connected with a panel 12. The shelf 10 and the panel are formed from a single piece of sheet metal bent along the line 14 to position the panel 45 at right angles to the shelf. The shelf may be provided with an upstanding flange 16. The shelf part is detachably connected with the lamp standard 18 through the medium of a clamp 20.

Referring to Fig. 4, the clamp 20 comprises a single piece of sheet metal bent back upon itself at 22 to provide a flat wall 24 and two ribs 26 of tapered configuration. The flat reaches 28 and 30 are bent to provide curved reaches 32 which substantially embrace the lamp standard 18, as illustrated in Fig. 2. The free ends of the

reaches 32 terminate in flares 34 to provide gentle curvatures.

The panel or wall 12 is provided with U-shaped lines of severance 36 and the material struck out to provide flanges 38 which have frictional relation with the ribs 26, as illustrated in Fig. 2. Clamp 20 is connected with the panel 12 by aligning the ribs 26 underneath the flanges 38 and pressing the ribs underneath the flanges. Immediately above the flanges 38 I strike out the metal to provide an abutment 40 which engages one end of the straight wall 24 to prevent relative movement between the shelf and the clamp with the device attached to the lamp standard 18, as illustrated in Fig. 3. To the reach 28 I fixedly 15 connect the head 42 of a bolt 44 which extends through a slot 46 in the reach 30. A wing nut 48 has threaded relation with the bolt 44 so that the curved reaches 32 may be firmly clamped upon the standard 18 (see Fig. 2).

Shelf 10 is severed and the material bent up to provide an ear 50 paralleling the panel 12. The ear 50 is spaced from the panel sufficiently far to accommodate a cigarette package 52 which is pressed between the ear and the panel with its 25 bottom resting on the shelf. I also provide the shelf 10 with two ears 54 which are so spaced as to fit snugly within the cover 56 of a match box. The cover 56 fits snugly between the ears 54 and the panel 12, and the ears are of sufficient 30 length to extend into the cover a sufficient distance to lend good support thereto. The match box is easily mounted on the shelf by merely pressing the cover of the box over the ears 54, at which time the flanges 58 on the ears press the 35 box of the match box outwardly of the cover 56 to render the matches 60 accessible, as indicated in general in Fig. 1. The upper part of the box may be thrown away in the usual manner. The cigarette package, as well as the matches, is held 40 firmly against the panel 12, and the shelf 10 is of sufficient area to provide space for an ash tray.

I prefer to connect the bolt 44 in fixed relation with the reach 28 as by welding. Slot 46 accommodates relative shifting of the bolt 44, as when 45 attaching or detaching the shelf. Reaches 28 and 30 are of a flexible nature so as to make the clamp applicable to standards of varying diameters. While I have illustrated the clamp in connection with a lamp standard, the clamp may be 50 attached to flat surfaces, such as, table tops, chair arms, or the like.

Frequently it may be desirable to attach the shelf to a horizontal support. To render the shelf applicable to such a support, I provide the 55

- panel 12 with a second pair of flanges 62 corresponding to the flanges 38 but arranged in right angular relation thereto. For use in connection with a horizontal support, the ribs 26 are associated with the flanges 62, at which time the shelf 10 will be supported in a horizontal plane with the clamp 20 connected with a horizontal support. An abutment 64, corresponding to the abutment 40, is associated with the flanges 62.
- 10 The device comprises two principal parts, namely, the clamp 20 and the shelf structure 10. The material of the panel 12 is formed to provide means cooperating with the clamp 20 for connecting purposes. Clamp 20 is applicable to 15 supporting members of varying proportions but may be effectively clamped thereto through the medium of the bolt 44. Both the clamp and the shelf structure are shaped from sheet metal and may be manufactured by simple bending 20 processes.

On the inner faces of the curved reaches 32 I position cushioning pads 66 of material such as 25 felt or rubber, thus protecting lamp standards and other furniture to which the clamp may be applied.

Without further elaboration, the foregoing will 30 so fully explain my invention that others may, by applying current knowledge, readily adapt the same for use under various conditions of service.

I claim:

1. A smoker's article comprising a shelf including an upstanding member, ears carried by 35 said upstanding member, a U-shaped clamp, the bight of the clamp being wider than the spacing of the legs adjacent thereto, to provide ribs, said ribs being slidably related to said ears for detachably connecting the parts, and means for drawing the legs of the clamp into clamping relation with a support.

- 40 2. A smoker's article comprising a shelf in-

cluding an upstanding member, ears carried by said upstanding member, a U-shaped clamp, the bight of the clamp being wider than the spacing of the legs adjacent thereto, to provide ribs, said ribs being slidably related to said ears for detachably connecting the parts, and means for drawing the legs of the clamp into clamping relation with a support, said legs having curved reaches for connection with a lamp standard.

3. A smoker's article comprising a shelf including an upstanding member, ears carried by 10 said upstanding member, a U-shaped clamp, the bight of the clamp being wider than the spacing of the legs adjacent thereto, to provide ribs, said ribs being slidably related to said ears for 15 detachably connecting the parts, means for drawing the legs of the clamp into clamping relation with a support, said legs having curved reaches for connection with a lamp standard, said means comprising a bolt having one end fixedly connected to one leg and the other end passing through a slot in the other leg, and a nut having threaded relation with the bolt.

4. A smoker's article comprising a shelf including an upstanding member, ears carried by 25 said upstanding member, a U-shaped clamp, the bight of the clamp being wider than the spacing of the legs adjacent thereto, to provide ribs, said ribs being slidably related to said ears for detachably connecting the parts, means for drawing 30 the legs of the clamp into clamping relation with a support, said legs having curved reaches for connection with a lamp standard, said means comprising a bolt having one end fixedly connected to one leg and the other end passing 35 through a slot in the other leg, a nut having threaded relation with the bolt, and means co-operable on the upstanding member and the bight of the clamp for restraining the two parts from relative movement in one direction.
